CLAIM

The ornamental design for a back shaver with folding handle, as shown and described.

DESCRIPTION

FIG. 1 is a top perspective view of the back shaver with folding handle showing the present design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines illustrate portions of the back shaver with folding handle that form no part of the claimed design.

1 Claim, 5 Drawing Sheets
